UNITED STATES PATENT OFFICE.

ARTHUR NUTT, OF KENMORE, NEW YORK, ASSIGNOR TO CURTISS AEROPLANE & MOTOR COMPANY, INC., A CORPORATION OF NEW YORK.

VALVE-OPERATING MECHANISM.

Refile for abandoned application Serial No. 9,167, filed February 14, 1925. This application filed February 14, 1927. Serial No. 168,204.

My invention relates to valve operating mechanism for internal combustion motors.

An object of the invention is to reduce the weight and the overall height of an internal combustion motor, and hence its frontal or projected area, by so forming the valve tappets thereof as to admit of their proper operation by the engagement therewith of the operating means or devices, the point or points of contact between said devices and said valve tappets being intermediately located between the ends of the valve tappet stems.

In the drawings, wherein like reference characters denote like or corresponding parts:

Fig. 1 is a plan view of one of the cylinders of a multi-cylinder internal combustion motor having its cylinders cast en bloc showing the valve operating mechanism of my invention;

Fig. 2 is a section on line 2—2 of Fig. 1;

Fig. 3 is a longitudinal vertical sectional view of a portion of one of the motor cylinders; the valve operating mechanism being illustrated in end elevation, and

Fig. 4 is a perspective view of one of the valve tappets.

In the embodiment of the invention selected for illustration, but one of the cylinders of a multi-cylinder internal combustion motor is shown. Such cylinder 10 is provided with two intake valves 11 and two exhaust valves 12, the intake valves being disposed at one side of a plane passing thru the axes of the cylinders and the exhaust valves 12 on the opposite side of said plane. Each pair of valves has associated with it a valve tappet 13. The valve tappets for the exhaust valves 12 and for the intake valves 11 are identical. Each tappet includes a shank or stem portion 14, a head portion 15 and an intermediate portion 16, said intermediate portion being formed by enlarging the stem 14 at or near its point of juncture with said head portion 15. The head portions 15 of the respective tappets extend longitudinally of the motor as indicated in Fig. 1, while the intermediate portions 16 of said tappets have formed therein transverse openings 17 into which the valve operating devices 18 are adapted to extend. The bottom wall 19 of each opening 17 constitutes

a bearing surface against which the operating device 18 is adapted to bear; said bearing surface in each instance being located intermediately of the ends of the valve tappet stems.

As illustrated, the operating devices 18 are in the form of rocker arms having intermediate pivot axes 20 extending parallel to the direction of the major axis of the head portions of the several tappets. At their outer ends said rocker arms are adapted to engage push rods 21 which are in turn adapted to be reciprocated by any suitable operating means (not shown). Thus organized, a single push rod 20 is provided for the proper operation of each valve tappet 13, and as the rocker arms 18 are not required to be located above the head portions of the valve tappets, obviously the overall height of the motor is very appreciably reduced. Moreover, thru the arrangement illustrated, the weight of the motor is somewhat reduced by reason of the decrease in size of the rocker arm supports and the push rods.

While I have described my invention in detail in its present preferred embodiment, it will be obvious to those skilled in the art after understanding my invention, that various changes and modifications may be made therein without departing from the spirit or scope thereof. I aim in the appended claims to cover all such modifications and changes.

What I claim is:

1. In valve operating mechanism for internal combustion motors, a valve tappet including a stem portion and a laterally extending head portion, a bearing surface formed on the valve tappet stem below said head portion, and operating means engageable with said bearing surface to actuate said tappet.

2. In valve operating mechanism for internal combustion motors, a valve tappet including a stem portion and a laterally extending head portion, said valve tappet having formed therein, below said head portion, an opening, and operating means engaging in said opening to actuate said tappet.

In testimony whereof I hereunto affix my signature.

ARTHUR NUTT.
